Filed Aug. 23, 1962, Ser. No. 71,429

Term of patent 14 years

(Cl. D9—6)

FIG. 1

FIG. 2

FIG. 4

FIG. 1 is a top plan view of a front floor mat for automobiles and the like embodying my new design;

FIG. 2 is an enlarged fragmentary cross sectional view taken on lines 2-2 of FIG. 1, the center of the side panel being broken away for convenience of illustration;

FIG. 3 is an enlarged fragmentary top perspective view thereof; and

FIG. 4 is an enlarged fragmentary top plan view thereof.

The bottom is essentially plain except for the corrugations on either side of the center, the bottom of said corrugations being substantially the same as the top shown.

I claim:

The ornamental design for a front floor mat for automobiles and the like, substantially as shown and described.
